UNITED STATES PATENT OFFICE.

HENRY SIEBEN AND WILLIAM J. STEVENSON, OF KANSAS CITY, MISSOURI; SAID SIEBEN ASSIGNEE TO PHILIP A. FUCHS AND WILLIAM HUNZIKER, JR., BOTH OF MILWAUKEE, WISCONSIN.

DEVICE FOR CLEANING, FLUSHING, AND DISINFECTION SEWERS.

1,036,735.

Specification of Letters Patent. Filed Aug. 27, 1913.

Application filed July 29, 1913. Serial No. 574,524.

To all whom it may concern:

Be it known that we, HENRY SIEBEN and WILLIAM J. STEVENSON, citizens of the United States, residing at Kansas City, in the county of Jackson and State of Missouri, have invented certain new and useful Improvements in Devices for Cleaning, Flushing, and Disinfecting Sewers, of which the following is a specification.

10 This invention relates to devices for cleaning, flushing, and disinfecting sewers, and is more especially adapted for use in the smaller sized sewers, which are usually circular in cross-section. Small sewer conduits 15 become clogged with rubbish, grease, and in some cases with growing vegetation, to such an extent that the sewer cannot perform its function.

20 The object of the invention is to provide a cleaning device embodying suitable revolving scrapers in connection with strong whirling jets of water, and a further object is to provide a device of the kind which is adapted to carry a cartridge of disinfecting or 25 grease-dissolving material.

The device in its preferred form comprises a water driven motor for actuating the revolving scrapers, the motor being a part of the device and carried thereby.

30 In order that the invention may be fully understood, reference will now be made to the accompanying drawings, in which:

Figure 1 is a longitudinal sectional view of a cleaner constructed according to the invention. Fig. 2 is a transverse sectional view on line II--II of Fig. 1, showing also a section of a sewer pipe. Fig. 3 is a detail sectional view on line III--III of Fig. 1, omitting certain parts. Fig. 4 is a detail view 40 of one of the runners and its mounting. Fig. 5 is a detail sectional view on line V--V of Fig. 1, of the rotary motor element and its housing. Fig. 6 is a detail view of the parts constituting the motor, one element being 45 partly broken away. Fig. 7 is an end elevation of the element 10. Fig. 8 is a vertical sectional view showing a line of sewers, the cleaner in position, the hose-connection, and means for swing the cleaner through the 50 sewer in two directions.

Referring to Figs. 1 and 2: The cleaner comprises a cylindrical body 1, provided with yieldably mounted straight parallel

runners 2 which are adapted to fit within a sewer pipe as 3, to support the cleaner centrally thereof. These runners are mounted between pairs of lugs 4, which are secured to the body 1. Each pair of lugs 4 is provided with a pin 5 which extends through a radial slot 6 in the runner 2. The lugs are 60 also provided with inner pins 7 upon which are mounted a bow spring 8, which bears outwardly upon the runner as shown in Fig. 4. The lugs are also provided with extra holes 9 for the runner pins 5, whereby the 65 runners may be set inwardly for use in smaller sewers.

Fixedly-mounted in one end of the body 1 is a motor element 10, hereinafter described. A shank 11 extends concentrically through 70 the piece 10, and has a nut 12 in contact with same. On the opposite end of the shank are nuts 13 which engage a clevis 14 having a cross-pin 15 to which a rope may be attached as shown in Fig. 1. An intermediate 75 portion of the shank 11 is threaded and carries a combined ball-bearing member 16 and a deflector 17 in the form of a convex disk, locked in place by a jam-nut 18. Parts 16 and 10 are provided with races to receive 80 ball-bearings 19. Rotatably mounted on and between said bearings are a motor element 20 and a hub or spider 21. Mounted on said hub or spider by bolts 22, is a loosening or tearing device, consisting of a pair of hooks 85 or horns 23, which extend to nearly the periphery of a pipe (Fig. 2) but stop short thereof so as to clear solid obstructions, as cement for example.

The non-rotary motor element 10 is 90 pierced with longitudinal, skewed channels 30 which are tapered in size in the direction in which the water is driven—i. e., toward the forward end of the device. The rotary motor element 20 is formed with inclined 95 grooves 31 and blades 31^a against which latter the streams from channels 30 discharge with considerable force and thus drive said motor element 20 at high speed. The number of grooves 31 is unequal to that of the 100 channels so that the latter can never be all obstructed at once by the blade ends 32 between the grooves.

32^a designates a spider secured to shank 11 by the rearmost nut 13 and a nut 13^a, for the 105 purpose of carrying forward, cans, stones,

or other obstructions too large to pass backward between the cylindrical body 1 and the interior of the sewer.

The rotary motor element 20 carries a plurality of brushes 24, which are preferably mounted as follows: Cast upon the hub or spider 21 are pairs of lugs 25 (see dotted lines, Fig. 2) between which are fastened the radial arms 26. The brushes are attached to said arms by bolts 27, and can be replaced when worn. Segmental reinforcing pieces 28 are secured to the arms 26 by bolts 29, and form braces for the hooks or horns 23, being secured to the latter by bolts 22.

Fixed upon the rear end of the body 1 is a ring 33, provided with opposite knuckle lugs 34 and 35. To lug 34 is pivoted a nipple 36, adapted for connection to a hose and forming an extension of the body 1. On the 20 nipple opposite its hinge is a lug 37. Pivoted to the aforesaid lug 35 is a latch 38, having a slot 39 to receive the nipple lug 37 and having a screw 40 adapted to engage the lug as shown. The ring 33 and the nipple 25 are grooved for the reception of a gasket 41. The nipple is reduced in diameter from that of the body 1, and is mounted as shown in order to permit the ready insertion and removal of a device having the full inner diameter of said body. The use of such a device is optional, and we have shown in the drawing a form of container which is well adapted for the purpose of charging the water with lye or a disinfectant. 42 designates 30 the tubular, perforated case or container, provided with feet 43 which support it in the tube 1. 44 is a central longitudinal, perforated tube supported by members 45 (Fig. 3) and contacting the shank 11, near which 35 point it has outlet orifices 46, for the water that may enter through the funnel 47 at the opposite end. 48 is a bail by which the device may be grasped. Before being inserted in the body 1, the outer case 42 is filled with 40 lye soap or with some pasty composition of lye or powerful disinfecting agent, or with any other suitable substance.

Each of the runners 2 is provided with a hole 49 or other means for the attachment of 50 a loop, as 50 in Fig. 2.

The mode of operation will now be described, reference being had to Fig. 8; 51 and 52 represent man-holes opening into a sewer pipe 3; the distance between the man-holes being of course reduced in the drawing. Two windlasses 53 and 54 are positioned over the respective man-holes, and pulleys 55 are fixed in the man-holes in any suitable manner. A hose 56 is coupled to the 55 nipple 36 and to a hydrant, and a rope 57 from the windlass at the lower of the man-holes is attached to loop 50 which is connected to the cleaner as aforesaid. The cleaner is lowered through the man-hole 51, 60 being then at the lower end of the sewer

pipe. The rope 58 from the other windlass is then "fished" or "floated" through the sewer and secured to the clevis 14. The water is then admitted to the hose 56, and a man operates the windlass 54 to draw the cleaner through the sewer. The water passes into the body 1, through the channels 30 and grooves 31, thereby rotating the motor element 20, the horns 23, and the brushes 24. The water discharges upon the deflector 17 and is thereby thrown obliquely outwardly against the walls of the sewer pipe and with a whirling motion, which contributes to the effectiveness of operation. The revolving hooks or horns 23 dislodge 70 and loosen rubbish and tear away any vegetation that may be rooted in the sewer. If the cleaner be charged with lye, the latter will tend to dissolve greasy deposits, which are usually found in sewers. It is obvious 75 that the deflector 17 might be omitted and the members 23 depended on for the active cleaning operation; or the parts 23 might be omitted and the scouring action of the water depended on. But the combined action of both is of course much more desirable than the unaided action of either of said devices. When the cleaner has traveled to the upper man-hole, the lower windlass 53 is operated until the cleaner has re-traversed the sewer to the starting end, during 80 which operation the hose 56 is drawn up as the cleaner moves. The hose and ropes may then be disconnected from the cleaner, and the apparatus moved to an adjacent portion 85 of the sewer.

It is obvious that air or other propelling fluid than water may be used to drive the motor 20.

Having thus described our invention, what we claim is:

1. A cleaning and flushing device for sewers, comprising a frame, a water motor, a hose connection for the motor, revoluble hooks driven by the motor, and revoluble brushes also driven by the motor, said brushes being adapted to clean the walls of a sewer by direct contact, said hooks being free of such contact.

2. A cleaning and flushing device for sewers, comprising a hollow body, runners on said body, a container within said body for lye or disinfectants, a hose connection to one end of the body, a water motor housed in the opposite end of the body, and revoluble cleaning members driven by the motor.

3. A cleaning and flushing device for sewers, comprising a hollow body, runners on said body, a container within said body for lye or disinfectants, a hose connection 115 hinged to one end of the body, a water motor housed in the opposite end of the body, and revoluble cleaning members 120 driven by the motor.

4. A cleaning and flushing device for sew-

ers, comprising a hollow body, a hose connection at one end the body, a water motor element fixed in the opposite end of said body, a shank passing axially through said 5 motor element and extending forwardly, a deflector adjustably mounted on said shank, a rotary motor element concentric with said shank, between the deflector and the fixed 10 motor element, ball bearings between the deflector and the motor elements, and revolute 15 cleaning members carried by the rotary motor elements.

5. A cleaning device for sewers, comprising a cylindrical body having a hose connection, runner supports fixed upon said body, runners mounted in said supports, bowsprings bearing outwardly upon said runners, and cleaning members carried by 20 said body; said runners being adapted to yield inwardly when impinging on solid obstructions.

6. A cleaning device for sewers, comprising a cylindrical body having a hose connection, straight parallel runner supports

fixed upon said body, runners movably 25 mounted in said supports, springs bearing outwardly upon said runners, and cleaning members carried by said body; said runners having radial slots, pins held by said supports and passing through said slots, and 30 cleaning members carried by said body.

7. A cleaning device for sewers, comprising a draft shank, a clevis secured to the shank, a tubular body secured to the shank, a hose connection to said body, a water 35 motor, revolute cleaners carried by said motor, and a deflector in the path of the water discharged from the motor, said deflector and motor being mounted concentrically upon said shank. 40
